UNITED STATES PATENT OFFICE.

ALMERIN H. LIGHTHALL, OF SAN FRANCISCO, CALIFORNIA.

UNDERGROUND CABLE-WAY.

SPECIFICATION forming part of Letters Patent No. 274,505, dated March 27, 1883.

Application filed November 18, 1882. (No model.)

To all whom it may concern:

Be it known that I, ALMERIN H. LIGHTHALL, a citizen of the United States, residing at San Francisco, in the county of San Francisco and State of California, have invented 5 certain new and useful Improvements in Underground Cable-Ways, of which the following is a specification.

My invention relates to improvements in the 10 construction of tunnels or passages for underground endless cables, and more especially to such cable-ways as are curved in the direction of their length; and the objects of my improvements are, first, to provide a cable-way and 15 "curve-room" so constructed that all necessary repairs to the cable-way and to the guiding-drums which carry the cable around the curve may be performed without removing any portion of the roadway or surface of the 20 street; second, to provide a curve-drum for a cable-way, so constructed as to permit of the removal and replacement of any portion of the 25 cable-bearing surface of the drum-rim; third, to provide an improved construction and arrangement of the guide-rails which conduct the 30 "grip" around the curve; and, lastly, to certain other details of construction, which will more fully appear hereinafter.

In the accompanying drawings, in which 35 similar letters refer to similar parts throughout the several figures, Figure 1 is a ground plan of the supporting-walls of my improved cable-way. Fig. 2 is a vertical cross-sectional view of one of the cable-passages and the 40 guiding-drums. Fig. 3 is a plan view of the drum-frame. Fig. 4 is a sectional view on line X X of Fig. 3.

The walls A A are given a degree of curvature which corresponds with the curve given to 45 the track-rails upon which the car travels. The transverse walls B B do not form a radial line with the walls A A, but are carried out on a line at right angles to a chord of which the walls A A form the arc. The walls B are 50 provided with openings or doorways C, which extend the whole height of the wall, and are sufficiently wide to admit of the passage of a workman from one compartment to the other. Upon the inner segmental walls are placed 55 girders or channel-beams D D, upon which is bolted the lower box or step, E, which carries

the vertical spindle F of the drums G, of which latter there are any desired number, arranged at stated intervals apart, and they are set as 60 as to bring the point of contact with the moving wire rope over the center of the openings C and beneath the grip-slot. The upper end of the drum-spindle is held within a box, H, secured in place upon the angle-beams I I, as 65 seen in Fig. 2. Upon all the walls, with the exception of such portions as support the 70 drums, I place girders or I-beams S S, in two or more vertical tiers, and connect and brace them by means of deck-beams or wooden timbers, or both. Upon the top tier of beams are closely 75 laid the timbers or planking, over which is spread the asphaltum or earth which forms the roadway. The grip-lever extends downward between the slot-irons J J, which are attached 80 by angle-irons to the deck-beams and girders. 70 The inner guide-plate, K, along which the grip passes, is made of angle-iron, and its vertical flange projects downward and overlaps the upper edge of the drum. The length of each 85 section of the guide-plate is equal to the distance between the centers of any two adjacent drums, and each section is secured at either end to the I-beams, resting upon the partition-walls B, which form the compartments within 90 which the drums revolve. By this construction I am enabled, by simply taking off one section of the guard-rail, to remove the wheel which is opposite to it from its compartment into the alley-way and roll it through the doors to the main hatchway. The outer guide-rail, 95 L, is canted by means of wedges M, so that the upper edge of the bearing or guide flange projects over and beyond the lower edge, as shown in Fig. 2, and upon which the outer pulley of the grip travels after the rope has been 100 dropped and the grip raised up. An opening, N, is made in the roadway, through which a rod may be passed and employed for drawing out the spindle of the drum, should it become necessary to remove the whole wheel. The drums over which the cable travels are made of cast-iron with radial arms, and the rim Q is hollowed out to receive a filling of wood, over which is placed in sections a band of iron having a concaved face, and the whole is secured to the rim by countersunk bolts. Flanges 105 O are cast upon the radial arms, and to them

are bolted the wooden filling or felly P P, the outer surface of which is covered with a tire or plate iron, which forms a continuous surface with the hollowed rim Q. The face of the 5 drum is somewhat beveled from the lower edge inwardly toward the upper edge; and the face of the drum may be covered with rawhide strings or bands wrapped around it to prevent the wearing away of the cable. Carrying reels 10 or pulleys R are placed at proper intervals apart to sustain the wire rope or cable and prevent it from falling below the lower edge of the drums. Beneath the line of the carrying-pulleys R, I place a series of troughs or 15 concave metal plates, which are made in sections, overlapping at their lower ends and secured by metal clips attached to the ends of the walls or supporting-beams, and are used for carrying off water and foreign substances 20 that may find entrance through the grip-slot. It will be seen by the above construction that I am enabled to provide a solid and substantial cable-way or curve-chamber, so arranged and proportioned as to admit of the 25 passage of workmen, and permit of the removal or replacement of any worn-out portions of the structure without the necessity of digging up and obstructing the street.

As a modification the short walls which support 30 the drums may be omitted and their place occupied by a casting having apertures through it to admit of the passage of a workman.

Having thus described my invention, what I claim, and desire to secure by Letters Patent, is—

35

1. A cable-way adapted for the curved portions of an underground cable-road, consisting of the segmental walls A A and transverse walls B B, provided with doorways C, and supporting a system of girders and beams, which 40 carry the roadway and guide the grip-bar and afford support for the steps and journal-boxes of the cable carrying and guiding drums, constructed and arranged substantially in the manner and for the purpose herein set forth. 45 and specified.

2. In an underground cable-way, the guide plates or rails K, when made in sections of a length equal to the distance between the centers of any two adjacent drums, and secured to 50 the intermediate supporting-beams, S S, resting upon the partition-walls of the drum-chambers, substantially as and for the purpose specified.

In testimony that I claim the foregoing I have hereunto set my hand and seal this 2d day of November, 1882.

ALMERIN H. LIGHTHALL. [L.S.]
